OUTDOOR YARD LIGHT HEAD

Harold P. Smith, Box 38, Panhandle, Tex. 79068

Filed July 5, 1967, Ser. No. 7,714

Term of patent 7 years

(Cl. D48—31)

The dotted lines in FIGURES 1 and 2 illustrate a manner of supporting the outdoor yard light head and are for illustrative purposes only.

I claim:

The ornamental design for an outdoor yard light head, as shown and described.
